CLAIM

The ornamental design for a desk, as shown and described.

DESCRIPTION

FIG. 1 is an isometric view of the desk;

FIG. 2 is a front view of thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines shown in the drawings are for the purpose of illustrating portions of the desk and form no part of the claimed design.
